ABSTRACT

A boring device for use in positioning and fastening hinge members between a door and frame member where the door panel has a mounting recess for receiving at least a part of the hinge. The device includes a screw clamp adapted to be positioned around an outer edge of the frame and guides for boring mounting holes in the frame. The clamp is provided with interchangeable U-shaped adaptor pieces for insertion within the mounting recess of the door panel. Various adaptor pieces for circular and elongated recesses of various sizes are provided to permit universal application of the boring device.

BORING DEVICE FOR SECURING HINGES AND THE LIKE

BACKGROUND OF THE INVENTION

This invention is directed to a boring device for positioning and fastening hinge members to a door and frame combination. More specifically, this invention is directed to a device for the proper positioning and mounting of so-called "invisible" hinge devices.

When dealing with invisible or covered type hinge parts, it becomes a difficult task to properly locate the holes for screws to mount these parts. It is almost impossible to position the door and frame with respect to each other and mark the mounting locations without producing an error. Usually a trial and error process is utilized to obtain a properly positioned arrangement.

Where an invisible hinge is used, a longitudinal recess is provided in the door panel into which the intermeshed hinge parts fold when the door is closed. The door is detachably connected by means of an angle piece to a pivotable hinge part mounted on the frame. The angle piece must be properly aligned with the door and set at a corresponding distance from the frame or the hinge part flush supported in the recess of the frame. In order to facilitate this mounting and eliminate the trial and error process, various boring devices of different types have been devised. These devices which are intended to provide a drilling or boring jig for properly aligning the members frequently do not meet the desired requirements with the necessary accuracy. In many occasions these devices are cumbersome or difficult to handle.

OBJECTS OF THE INVENTION

An object of the present invention is to provide a boring device which is not only easy to manipulate but which is accurate in properly positioning the frame and door relative to each other.

A further object of this invention is to provide a boring jig device for the mounting of flush hinge parts which is both inexpensive to manufacture and economical to use in saving time in performing the necessary mounting operation.

A further object of this invention is to provide a boring device which is universal and can be used in mounting hinges of various sizes and configurations.

SUMMARY OF THE INVENTION

In the present invention, a screw lamp device is provided having a back supporting leg and a longitudinal edge parallel to the axis of the mounting screw. The back supporting leg includes the boring jigs or jacks through which the drill or bit is inserted for cutting the mounting holes. The elongated edge of the clamp is provided with interchangeable slide-like adaptor pieces which fit over the outer surface and end of the elongated edge. The adaptor pieces, having an internal channel fitting the edge of the clamp, are of various external dimensions to be inserted in a recess of corresponding size in a door. The size of the recess corresponds to the size of the hinge members used. A stop on the elongated edge portion of the clamp properly positions the clamp with respect to the recess.

The boring device of the present invention can also be used with hinge members wherein the hinge part mounted in the door is of a cylindrical configuration.

The recess provided in the door is thus a round hole or bore. The adaptor piece for the boring clamp in such case may be provided with a pivoted circular recess. Thus, the present invention can be used with the elongated recess type hinge or the circular mounted hinge.

With the present invention, a single boring jig clamp device is capable of performing the mounting operation for any size of hinge or configuration desired. Thus, a considerable savings is provided in the facilitation of handling and the stocking of a minimum number of parts to mount different sizes and shapes of hinges.

BRIEF DESCRIPTION OF DRAWINGS

15 Other objects of this invention will appear in the following description and appended claims, reference being made to the accompanying drawings forming a part of the specification wherein like reference characters designate corresponding parts in the several views.

20 FIG. 1 is a perspective view of the boring device of the present invention and the elongated mounting recess in a fragmentary view of a door;

25 FIG. 2 is a sectional view of a clamp adaptor piece taken along the line II-II of FIG. 3;

FIGS. 3 and 4 are side and top views respectively of a clamp adaptor piece according to the present invention;

30 FIG. 5 is a sectional view of another embodiment of the clamp adaptor piece according to the present invention taken along the line V-V of FIG. 6;

FIGS. 6 and 7 show a side and top view respectively of the further embodiment of the clamp adaptor piece;

35 FIG. 8 is a diagrammatic view of the boring device mounted within the door recess and secured to the frame for proper drill positioning;

FIG. 9 is a side view of the adaptor piece of FIG. 3 mounted on the edge of the boring device; and

40 FIG. 10 is a side view showing the further embodiment of the adaptor piece of FIG. 6 mounted on the edge of the boring device.

DESCRIPTION OF SPECIFIC EMBODIMENTS

45 More specifically, referring to FIG. 1, the boring device of the present invention includes an adjusting screw spindle 2, a pressure plate 3 secured thereon, and a handle 4. The pressure plate may be mounted for rotation with respect to the screw 2 which is conventional in a screw clamp device. Yoke bar or elongated edge member 9 has an outwardly extending stop member 10. If desired the stop member 10 may extend above and below the surface of the elongated edge member 9. A lateral stop 11 is provided along the inside edge of the elongated member 9. The stop 11 provides an abutment face for positioning the clamp device against the rear edge of the door 12 and at the same time provides an abutment surface for the edge of the frame positioned between a leg 7 and the pressure plate 3.

50 55 60 65 The screw clamp device of the present invention is designed basically in the configuration of the conventional C-clamp, and includes the yoke shown generally at 5 with a generally perpendicular leg 6 through which the screw spindle 2 is threaded and a back-up leg 7. Boring jacks or drill guides 8 are positioned in spaced relation within the leg 7 and are generally perpendicular to the inside surface of the leg 7. The

space and location of the bore jacks 8 can be arranged as desired for the frame mounting holes depending on the location of the screw holes in the hinge plate to be secured to the frame.

An elongated recess 15 is provided within the edge and rear surface of the door panel 12 for the recessed mounting of the door hinge element. The elongated side member 9 is fitted with a connecting surface or fixture adaptor 14 which is narrow enough to fit within the most narrow recess size anticipated.

An adaptor piece 16 is shown in FIGS. 2 - 4 and is provided in U-shaped cross-section with an outer flap or top piece 17. The internal channel 16a of the adaptor piece fits securely on the connecting surface 14 of the boring device 1. Adaptor pieces of varying width may be provided as needed to fit any of the common recess sizes which are required for various sized hinge members. The internal channel 16a of each such adaptor piece, however, is the same size to fit the connecting surface 14. In this way a plurality of adaptor pieces 16 may be provided to allow the boring device 1 to be used with any size recess 15. A hole 18 is provided in the flap or top 17 so that the piece 16 may be secured by means of a screw or the like to the front edge of the fitting piece 14. (See FIG. 8).

As shown in FIG. 8, with the proper adaptor piece 16 mounted on the fitting piece 14, the boring device 1 is slidably inserted into the recess 15 until the stops 10 and 11 are positioned flush against the edge and rear surface of the door 12. The screw 2 is then turned by the handle 4 until the pressure plate 3 firmly holds the frame 13 against the surface of the leg 7. Once the boring device is properly positioned on the frame, the door 12 may be removed and the mounting holes may be bored in the frame by inserting a proper sized drill to the desired depth through the bore jacks or guides 8.

Another embodiment of an adaptor piece is shown in FIGS. 5 - 7. This embodiment is used with those types of hinges which utilize a circular mounting recess 15a in the door 12. The adaptor piece 19 includes a retaining plate 20 pivotally mounted on the outer edge surface thereof. Internal channel 19a is sized to fit the fitting piece 14 of the boring device 1. The outer edges of the plate 20 are rounded in a circular configuration 22, the radius of which matches the radius of the circular recess 15a. If desired the plate 20 may be increased in area so as to form a complete cylindrical member. The thickness of the plate 20 is designed to insure proper alignment of the boring device 1 with respect to the recess 15a in the door 12. The adaptor piece 19 includes the top piece 23 through which bore 18a is provided. A screw or the like can be used to secure the adaptor piece 19 to the front side of the fixture element 14 as shown in FIG. 10.

While the boring device for mounting hidden hinge members to frames and doors has been shown and described in detail, it is obvious that this invention is not to be considered as being limited to the exact form disclosed and that changes in detail and construction may be made therein within the scope of the invention without departing from the spirit thereof.

I claim:

1. A boring device for locating hinge mounting holes wherein a mounting recess is provided in a first member and mounting holes are to be located in a second

member, said device comprising

- a. adjustable clamp means adapted to be attached to the second member,
- b. an adapter device removably mounted on said clamp means and having an external surface of predetermined size and shape to be received and precisely fit within said mounting recess in said first member, and
- c. drill guide means arranged on said clamp means for locating said mounting holes in said second member,
- d. whereby with said adapter device retained in said recess of said first member, said first member may be properly positioned with respect to said second member and then said clamp means secured to said second member to locate said mounting holes therein.

2. A boring device as defined in claim 1 wherein said clamp means includes an elongated mounting portion having three parallel surfaces and said interchangeable adaptor device includes a U-shaped channel arranged to fit about and contact said surfaces of said mounting portion whereby said adaptor device may be conveniently mounted on and removed from said clamp means.

3. A boring device as defined in claim 2 wherein said elongated mounting portion includes stop means for positioning said clamp means with respect to two surfaces of said first member.

4. A boring device as defined in claim 1 wherein said adaptor device includes a pivotally mounted plate, the opposite ends of which are rounded to be received in a circular recess in said first member.

5. A boring device as defined in claim 1 wherein said adaptor device includes a plate having a cylindrical configuration to be received in a circular recess in said first member.

6. A boring device as defined in claim 2 wherein said adaptor device includes a portion closing one end of said channel, means being provided to secure said portion to said clamp means when said adaptor device is positioned thereon.

7. A boring device for locating hinge mounting holes, said device being adapted for positioning in a mounting recess provided in a first member while mounting holes are located in a second member, said device comprising

- a. adjustable clamp means to be attached to the second member,
- b. a plurality of adaptor devices, each being selectable to be removably mounted on said clamp means, each of said adaptor devices having a different external surface of predetermined size and shape and arranged to be received and precisely fit a mounting recess in said first member, and
- c. drill guide means arranged on said clamp means for locating said mounting holes in said second chamber,
- d. whereby with the appropriate one of said adapter devices retained in the recess of said first member, said first member may be properly positioned with respect to said second member and then said clamp means secured to said second member to locate said mounting holes therein.
